ELECTRON TUBE WITH LUMINESCENT SHIELD, ESPECIALLY TUNING TUBE

Werner Jacobi, Erlangen, and Hermann Hinderer, Marloffstein, near Erlangen, Germany, assignors to Siemens & Halske Aktiengesellschaft, Berlin-Siemensstadt, Germany, a corporation of Germany

Application October 3, 1950, Serial No. 188,162
In Germany September 9, 1949

8 Claims. (Cl. 313—107.5)

1

This invention is concerned with electron discharge devices, especially tuning tubes, having fluorescent electrodes which are rendered luminous to produce for indicating purposes patterns of light in response to applied voltages.

The object of the invention is to provide a discharge device of the above noted type having a fluorescent electrode which comprises an elongated transparent support, e. g., a glass support, carrying a narrow strip or band of fluorescent substance substantially throughout its longitudinal extent. The fluorescent substance is rendered luminous responsive to applied voltages and produces a narrow, luminous indicating column of different length according to the voltage applied. This luminous indicating column may be viewed through the transparent support along lines of observation which lie entirely outside of the remaining electrode members of the discharge device, thus permitting observation of the entire area of the luminous column and thereby providing for clear and unobstructed indication. The various elements of the new structure are arranged in a manner to save space.

The term "transparent" is intended to embrace the meaning usually attached to the term "translucent," or similar language. The term "glass" employed herein with reference to the material used for the support of the fluorescent substance, unless otherwise restricted, is intended to include glass as such, as well as any other desired and suitable material which is transparent or substantially transparent, so as to satisfy the requirements of the invention.

The fluorescent substance may be provided on the transparent support in the form of a thin, striplike layer of such moderate thickness as to prevent charging. The support for the fluorescent substance may be provided with a suitable conductive substantially transparent coating.

The use of a glass rod of cross-sectionally substantially cylindrical or heart shaped configuration was found particularly suitable. Such a glass body may be made in the form of a thin rod of a few millimeters thickness. The fluorescent substance may be applied to the glass rod by powdering or by sedimentation with the use of suitable masks. The glass rod may also be provided with a shallow groove, e. g., by etching, to which the luminescent substance adheres while it is wiped off from the remainder of the rod. The indication provided by the luminous fluorescent substance on the glass rod may be observed either obliquely from the front or from

2

in rear, the directions of viewing which are not obstructed by members of the remaining electrode system of the discharge device.

The optical properties of the transparent rod may be utilized by giving it a proper shape to produce an apparent increase in the brightness or a magnification of the luminous indicating column, thereby improving the indication.

Since the electrodes are in the structure according to the invention outside of the observation field, they may be formed and disposed so as to produce particularly favorable electrical and electron-optical effects. For example, it is in accordance with another object possible, to provide between the cathode and the support for the fluorescent substance a control electrode which is made in the shape of a shutter forming a wedgeshaped cutout. The size of such shutter may be so dimensioned that it does not adversely affect the observation of the indication. The invention also permits auxiliary utilization of the space around the cathode (which is outside of the field of observation), for accommodating amplifier means and the total cathode length may thus be utilized as the electron source for such amplifier means. The amplifier means may be preferably arranged upon the side of the cathode which is opposite to the electron stream. The discharge device may be in the form of a four- or five pole tube and the amplifier means may be arranged for the amplification of the high frequency or may be employed as a low frequency starter stage. The control electrode of the indicating system may be so constructed and disposed that it controls the entire emission of the cathode in a boosting sense.

The invention will now be described more in detail with reference to the accompanying drawings, wherein

Fig. 1 illustrates in schematic perspective and exploded view the principal electrode members of an electron discharge device embodying features of the invention;

Fig. 2 indicates in like schematic manner another embodiment in diagrammatic sectional view;

Fig. 3 illustrates, in cross-section, a heart-shaped form of the transparent support of Fig. 1; and

Fig. 4 illustrates, in cross-section, a flat elongated striplike form of the transparent support of Fig. 1.

The cathode in Fig. 1 is indicated by numeral 1. It is a tubular cathode carrying on the outside an emission layer and comprising in usual

manner interior heating means 2. The shutter 3 has a wedgelike or V-shaped cutout and serves as a control electrode. The fluorescent substance 6 is carried in a longitudinal groove 8 of the support 7, which may be a glass rod or the like. There are two anode members 4 and 5 which are made of suitable sheet material and disposed so as to form a gap therebetween, as shown. The support 7 is disposed so that the groove 8 carrying the fluorescent substance faces the cathode through the gap formed by the anode members 4 and 5.

The glass support 7 may be ground longitudinally so as to form a plane surface (instead of the groove 8 shown) for receiving the fluorescent substance. The glass rod may also be cross-sectionally heart shaped, as shown in Fig. 3 or may have another suitable cross-sectional configuration such as shown in Fig. 4 so as to provide for desired optical effects, e. g., magnification of the luminous column formed by the fluorescent substance or increase of the brightness thereof, as mentioned before.

In the embodiment shown in Fig. 2, numeral 3 indicates the cathode which may be of cylindrical shape. A strip or band shaped cathode or a cathode of different suitable form may of course be provided as desired. A support 10 is provided which carries the fluorescent substance and a control electrode 11 is disposed between the support 10 and the cathode. The electrode 11 may be made in the shape of a shutter having a wedgelike opening, as described in connection with the electrode 3 of Fig. 1.

The cathode 9 may be used throughout its length, in a suitable circuit, as a part of an amplifier tube system. The electrodes surround the cathode 9 semi spherically as shown. The individual electrodes are indicated schematically. Numeral 12 represents the anode, 13 a brake grid, 14 a screen grid, and 15 designates a control grid. The structure may therefore form a pentode for high- and intermediate frequency amplification. If desired, the pentode may also be utilized as a low frequency amplification tube.

Changes may be made within the scope and spirit of the appended claims.

We claim:

1. In an electron discharge device having a cathode, an anode and a control electrode, a fluorescent electrode comprising an elongated support made of glass or the like transparent material, a strip of a fluorescent substance carried by said elongated transparent support only on the side thereof which faces the cathode, said fluorescent substance being rendered luminous to provide a bright indicating column of variable length responsive to varying voltages applied to said discharge device, said transparent support permitting unobstructed observation of the entire luminous column throughout its entire area from a direction in back of the strip of fluorescent substance carried thereby.

2. The structure defined in claim 1, together with a substantially transparent layer of a conductive material carried by said transparent support underneath said fluorescent substance.

3. The structure defined in claim 1, wherein said transparent support is of cylindrical cross-section.

4. The structure defined in claim 1, wherein said transparent support is of heart-shaped cross-section.

5. The structure defined in claim 1, wherein said transparent support is a flat elongated strip-like member.

6. The structure defined in claim 1, wherein said control electrode is a flat sheet member in which is formed a wedge-shaped cutout, said member being disposed between said cathode and said transparent support for said fluorescent electrode to control the emission of said cathode.

7. An electron discharge device comprising a cylindrical cathode, a pair of anode members, said anode members being disposed to form an elongated gap therebetween, a control electrode having a wedge-shaped cutout formed therein, said control electrode being disposed between said cathode and said anode members, a fluorescent electrode disposed in back of the gap between said anode members, said fluorescent electrode comprising an elongated support made of glass or the like transparent material, a narrow strip of a fluorescent substance carried by said transparent support only on the side thereof which faces said cathode through said gap between said anode members, said fluorescent substance being rendered luminous to form a bright indicating column of variable length responsive to varying voltages applied to said discharge device, said transparent support permitting unobstructed observation of the entire luminous indicating column throughout its entire area from a direction in back of the strip of the fluorescent substance carried thereby.

8. An electron discharge device comprising a cylindrical cathode, a semi-spherical anode with its concave side radially spaced from said cathode, a plurality of semi-spherical grid electrodes disposed between said cathode and said anode, a flat control electrode in which is formed a wedge-shaped cutout, said control electrode being disposed adjacent said cathode with one side thereof facing said cathode and the inside of the semi-spherical electrodes in back of said cathode, a fluorescent electrode disposed adjacent to said control electrode on the other side thereof, said fluorescent electrode comprising an elongated support made of glass or the like transparent material, a strip of a fluorescent substance carried by said transparent support only on the side thereof which faces said control electrode, said fluorescent substance being rendered luminous to form a bright indicating column of variable length responsive to varying voltages applied to said discharge device, said transparent support permitting unobstructed observation of the entire luminous indicating column throughout its entire area from a direction in back of the strip of the fluorescent substance carried thereby.
